BRAKE MECHANISM FOR WINDING REELS

Alvin Spencer, Whitinsville, Mass., assignor to
Whitin Machine Works, Whitinsville, Mass., a
corporation of Massachusetts

Application December 28, 1936, Serial No. 117,703

4 Claims. (Cl. 28—51)

This invention relates to a reel of the "dresser" type such as is used in the preparation of yarn for warping. The purposes and general operation of such reels are well known but may be briefly stated as follows:—

Threads or yarn ends are brought to the reel from a great number of spools mounted in an adjacent creel and are secured to a section of the drum or winding member, which is then rotated 10 to wind the yarns on the drum. During the winding operation, the entire reel is automatically traversed so that the yarns form a diamond-shaped section on one portion of the drum. Successive overlapping sections are thereafter 15 added along the length of the drum. When the drum is full, all of the yarns in all of the sections are simultaneously unwound from the drum and are transferred to a loom warp beam.

A reel of this general type is shown in the 20 prior patent to Thiel, No. 934,580.

It has been proposed to provide a warp stop motion for such reels, which will immediately stop the reel drum on breakage of one or more warp threads. Such a stop motion is shown for 25 instance in the prior application of Fulton Rindge, Serial No. 104,678, filed October 8, 1936. This application discloses a brake mechanism controlled by a warp stop motion and operated through a solenoid on warp breakage and simultaneously with the opening of the driving motor 30 circuit.

It is also desirable to apply a relatively lighter braking or tensioning force to the winding drum during the unwinding and beaming of the warp 35 sections which have been wound thereon.

It is the general object of my invention to provide improved braking or tensioning devices for the purpose indicated, by the use of which any desired resistance to backward or unwinding motion of the drum may be produced. This resistance is preferably in such amount as will cause the warp threads to be firmly wound on the loom warp beam and as will further prevent overrunning of the drum in an unwinding direction when 45 rotation of the warp beam is stopped.

To the attainment of this object, I preferably provide one or more weighted members adapted to apply a desired resistance to drum rotation and manually movable to operative or inoperative 50 positions. In the preferred form, each weighted member coacts with parts of the previously mentioned braking mechanism which is controlled by the warp stop motion.

My invention further relates to arrangements 55 and combinations of parts which will be herein-

after described and more particularly pointed out in the appended claims.

A preferred form of the invention is shown in the drawings, in which

Fig. 1 is a sectional side elevation of a reel embodying my improvements, taken along the line 1—1 in Fig. 2;

Fig. 2 is an end elevation of the reel, looking in the direction of the arrow 2 in Fig. 1;

Fig. 3 is a detail sectional view to be described; 10

Fig. 4 is an enlarged end elevation of certain parts shown in Fig. 2 which comprise my improvement;

Fig. 5 is a partial rear elevation, looking in the direction of the arrow 5 in Fig. 4; and 15

Fig. 6 is a detail view, partly in section, looking in the direction of the arrow 6 in Fig. 5.

The reel to which I have applied my invention comprises a drum 10 mounted on a shaft 11 and driven from a motor M through suitable reduction gears 12 and 14. The drum 10 has an enlarged conical portion 15 at one end, and the yarns are wound thereon in diamond-shaped sections as indicated in dotted lines in Fig. 1.

Brake members 20 coact with brake flanges 21, 25 preferably formed on the discs or spiders 22 which support the drum 10 on the shaft 11. The brake members 20 are pivotally connected in pairs as indicated at 25 (Fig. 2) and the free ends of the brake members 20 engage a flattened or 30 slabbed off cam portion 26 (Fig. 6) of a collar 27 fixed on a brake shaft 28.

The shaft 28 is mounted in fixed bearings and is provided with an arm 30 (Fig. 4) connected through a swivel member 31 and connecting rod 32 to a plunger 33 which is slidable in a solenoid coil 34. When the solenoid is energized through breakage of a warp thread, the plunger 33 is moved to the right in Fig. 4, thus rotating the shaft 28 and causing the cam portion 26 of the 40 collar 27 to separate the brake members 20, thereby applying braking pressure to the flanges 21. A spring 36 (Fig. 6) contracts the brake members 20 when they are released.

This brake mechanism is preferably duplicated 45 at each end of the drum but the two brake mechanisms are operated simultaneously on occasion of warp breakage. For a more complete description of the construction and operation of the mechanism thus far described, reference is 50 made to the Rindge application above identified.

In carrying out my improvements, I provide a lever 40 (Figs. 4 and 5) loosely mounted on the shaft 28 between the arm 30 previously described and a collar 41. The lever 40 is preferably grad- 55

uated as indicated in Fig. 4, and a relatively heavy weight W is slidable on the graduated lever 40 and may be secured in any desired position thereon.

5 The lever 40 is also provided with an offset arm 45 in which a setscrew 46 is threaded and is secured by a lock nut 47 . The end of the setscrew 46 engages a lug 50 on the arm 30 which, as previously stated, is keyed or otherwise fixed 10 to the brake-applying shaft 28 .

During the normal operation of the reel in winding yarn thereon, the lever 40 and weight W will be in the inoperative position shown in broken lines in Fig. 2, with the setscrew 46 out of contact with the lug 50 . The braking mechanism is thus entirely under control of the warp stop motion through the solenoid 34 during the operation of winding yarn on the drum.

When, however, yarn is to be unwound therefrom, the solenoid coil 34 will be necessarily de-20 energized and the usual brake-applying mechanism will be inoperative.

In order to secure a desired but relatively lighter resistance to backward motion of the 25 drum during the unwinding operation, the operator swings the levers 40 and weights W to the position shown in Fig. 4 and in full lines in Fig. 2. In this position, each weight W will act through its lever 40 , screw 46 , lug 50 and arm 30 to apply 30 turning pressure to the associated shaft 28 and cam portion 26 , thereby applying the brakes.

The weights W will be adjusted along the levers 40 to produce sufficient pressure to overcome the springs 36 and to apply the necessary resistance 35 or tension to the drum 10 to retard the unwinding thereof. This resistance should be great enough to insure a firm and close winding of the warp threads on the loom warp beam, and also to prevent overrunning of the drum in a backward direction and loosening of the threads when rotation of the loom warp beam ceases abruptly. The graduations on the levers 40 assist the operator in estimating the applied tension and also in equalizing the tension at both ends of the drum.

40 After the unwinding operation, the levers 40 and weights W are swung in the direction of the arrows a in Figs. 2 and 4 to their inoperative positions, where they remain during a subsequent filling of the drum. The weights W when once set commonly require no further adjustment unless a change in operating conditions or 45 in character of yarn occurs.

Having thus described my invention and the advantages thereof, I do not wish to be limited to the details herein disclosed, otherwise than as set forth in the claims, but what I claim is:—

1. In a reel, a winding drum, brakes for said 5 drum, means to apply said brakes to stop the drum on warp breakage, and additional and independently acting means to apply said brakes to yieldingly resist backward rotation of said drum during the unwinding of yarn therefrom, 10 said additional means being manually movable into and out of position to coact with said brakes while maintaining the adjustment of said additional means in all positions thereof, whereby the same yielding resistance is applied whenever 15 said additional means is operatively positioned.

2. In a reel, a winding drum, brakes for said 20 drum, means to apply said brakes to stop the drum on warp breakage, additional and independently acting means to yieldingly apply said 25 brakes to resist backward rotation of said drum during unwinding of yarn therefrom, said additional means being manually movable to operative and inoperative positions, while maintaining the adjustment of said additional means in all 30 positions thereof, whereby the same yielding resistance is applied whenever said additional means is operatively positioned and means to vary the resistance of said additional means.

3. In a reel, a winding drum, brakes for said 35 drum, means to apply said brakes to stop the drum on warp breakage, and additional and independently acting means to yieldingly apply said 40 brakes to resist backward rotation of said drum during unwinding of yarn therefrom, said additional means including levers manually movable to operative and inoperative positions and weights 45 adjustably mounted on and secured to said levers.

4. In a reel, a winding drum, brakes therefor, electro-magnetic means to apply said brakes on 50 warp breakage, and additional independently acting mechanical means to apply said brakes to provide yielding resistance to backward rotation of said drum during the unwinding of yarn therefrom, said latter means being manually 55 movable to operative and inoperative positions while maintaining the adjustment of said additional means in all positions thereof, whereby the same yielding resistance is applied whenever said additional means is operatively positioned. 50

ALVIN SPENCER.
